UNITED STATES PATENT OFFICE.

SAMUEL WOLK, OF DORCHESTER, MASSACHUSETTS.

DESIGN FOR A TOY WHISTLE.

60,437.

Specification for Design. Patented Feb. 14, 1922.

Application filed October 6, 1920. Serial No. 415,168. Term of patent 14 years.

To all whom it may concern:

Be it known that I, SAMUEL WOLK, a subject of the Russian Government, residing at Dorchester, in the county of Suffolk and State of Massachusetts, have invented a new, original, and ornamental Design for a Toy Whistle, of which the following is a specification, reference being had to the accompanying drawing, forming part thereof.

Fig. 1 is a plan view and Fig. 2 is a side elevation of a toy whistle showing my new design.

I claim:

The ornamental design for a toy whistle as shown.

SAMUEL WOLK.
